AUTOMATIC FLOW CONTROL MEANS

Charles H. Smith, Portland, Oreg.

Application December 13, 1938, Serial No. 245,408

10 Claims. (Cl. 137—68)

This invention relates to automatic flow control means for hydraulic systems and is peculiarly adapted for use in controlling the amount of flow from laterals into a main trunk sewer in sewage disposal systems in large cities and it will be so illustrated and described for the purpose of this disclosure.

It is an object of the present invention to devise mechanism to regulate flow volume in a relatively predetermined proportion from a plurality of laterals into a trunk line, in such manner that each will contribute its predetermined part of the whole capacity of the trunk line, regardless of the hydraulic head tending to dump the entire flowage of one lateral into the trunk, at the expense of carrying capacity to be apportioned to other laterals further along the trunk towards the point of final disposal.

In sewage disposal systems the gathering of sewage from original sources is accomplished by branched lateral systems of pipes, laid to a hydraulic gradient according to limitations imposed by topography. For example, if a considerable area to be drained lies along the bank of a river, say for a distance of several miles, the river grade forms the natural drainage outlet for that district. The laterals, however, owing to surface irregularities, must in general be normal to the river, reaching it at a number of separated points along its bank, the logical and only place for the trunk sewer if gravity flow is to be depended upon to any extent. Maximum storm-water conditions usually connote overflow, as clear as may be from the semi-solids.

As is well known, the semi-solids from the laterals will tend to the bottom of the laterals, especially if an enlargement or basin be provided to check the velocity of the flow at the terminus or point of juncture with the trunk. Overflow outlets will be provided to dispose of storm water surplus but it is very important that each lateral have reserved its allotted portion of the whole capacity of the trunk, that the semi-solids shall for the most part at least go to the trunk and not into the river through the overflow, during excess water periods.

Apparatus to admirably accomplish the functions heretofore set out are illustrated in the accompanying drawings and described in the specification, but are not intended as limiting the invention to the one embodiment, the scope of the invention to be ascertained from the claims which follow.

Drawings of the particular embodiment chosen to illustrate the invention herewith, are in three

sheets consisting of six related figures, as follows:

Fig. I is a vertical section of a preferred form, to be described in detail;

Fig. II is a plan view of Fig. I;

Fig. III is a section on the line III—III, Fig. I;

Fig. IV is a section taken on the line IV—IV of Fig. I;

Fig. V is a section on V—V of Fig. I; and

Fig. VI is a section on VI—VI, Fig. I.

In the drawings, 1 is a conduit communicating with an adjacent trunk sewer, not shown, and 2 is a lateral, the entire flow from which is to be delivered to the conduit 1, under normal conditions, and 3 is a valve opening through which the flow takes place. Under expected normal conditions, the valve 4 will be at rest in about the position shown, that is to allow full capacity of the opening 3.

This lateral 2 will be only one of a number of lines that are designed to discharge into the trunk and for purpose of illustration it will be assumed to be about the center of the drainage district served. Thus under abnormal conditions, if the laterals above it have not been controlled, the trunk carrying capacity will have been satisfied by laterals discharging from a higher level; hence the particular one shown would have to overflow its entire volume.

Each of the other laterals will, however, have been equipped with controls similar though perhaps varying in the size of the valve opening 2 and its cooperating valve 4. Mechanism to operate the valve flow and deliver a predetermined quantity of flow to the conduit 1 will now be described.

The lateral discharges into the chamber 6 which breaks the flow velocity, tending to keep the semi-solid parts of the flow at the bottom. As the flow begins to exceed the carrying capacity of the valve opening 3, a hydraulic head develops in the chamber 6, being reflected in the float well 7, in communication therewith by the screened opening 8.

A float 9 is provided with guides such as 10, 11 and 12. The float rises with the liquid in the well 7. The float 9 is provided with a central opening in which is fixed a plural thread nut 13 which is an easy fit on the threaded shaft 14, the threads in this case being quadruple.

The shaft 14 is mounted revolvably in the lower bearing 15 and the upper bearing 16 and carries a rigidly fixed worm 17 that engages with the double roller head 18, made rigid with the lever 19. It will be noted that the worm 17 and the double roller head 18 have the same relationship

as a relative low pitch worm with sector of a worm gear, that is the worm runs the gear easily but the locking characteristic of a worm and gear is present to oppose revolution from oppositely acting forces. This constitutes a very effective irreversible reducing motion between the float and the valve.

The thread of the worm 17 is made with a differential or changing pitch to give a faster motion 10 when the valve 4 starts to close than when it is further along towards closure, because the friction of fluid passing between the valve 4 and the valve seat 4a increases as the square of the velocity; hence a uniform closing of the valve will not 15 result in a maintained volume which is corrected by the variable pitch. This variable pitch must be computed for each size of valve and seat; therefore the indication is diagrammatic and sufficient for the engineer skilled in such design 20 when his attention is called to its necessity.

The lever 19 is fulcrumed on the standard 20, which is movably attached to the base 21 by cap-screws 22, or other preferred means. It passes through the sleeve 23, provided with trunnions 24 25 rockably engaged by the standard 20; hence the relative length of the two arms of the lever 19 may be changed for adjustment to operate valves 4 of varying size.

The operated arm of the lever 19a is pivotally connected to the valve stem 25 by the trunnioned sleeve 26 which is quite similar to the one shown at 23. The valve stem 25 is constrained to lineal vertical movement by suitable bearings such as 27 and 28; hence any rise of the float 9 causes 30 the worm 17 to turn proportionately to such rise, which turning movement is translated into a downward movement of the valve stem 25, reducing the area of the annular opening 3a, carefully designed to have the same carrying capacity 35 as the opening 3 when the relative position of the valve 4 is as shown. If the apparatus is properly designed, each increment of increase of hydrostatic head over the valve 4 will be reflected as a corresponding rise of the float 9, which, as 40 explained, will be translated into a relative closing movement of the valve 4 with respect to the opening 3a and the actual flow therethrough will be the same within close limits whether the float 45 is up, down or in any intermediate position. The 50 actuating mechanism is so proportioned that complete closure of the valve 4 never occurs.

Counterbalance means for the valve stem 25 is shown by the weights 30 attached to cables 31 55 passing over the pulleys 32 and attached to the clamp 33.

Since the buoyancy lift of the float 9 will ordinarily be less than its weight, an equalizer is shown as the drum 35, the cable 36, the pulley 60 37 and the counterweight 38 so arranged as to assist the turning moment of the shaft 14 when the hydrostatic head tends to raise the float 9.

The exemplification as described is for a sewage system but quite obviously it can be arranged without substantial change to deliver a relatively fixed amount of water from a main irrigation ditch to a lateral, with a varying head in the main ditch. It has many other applications which will be at once apparent to the hydraulic engineer.

The devices of the present exemplification of the invention have been explained with a considerable attention to detail, so that the art may fully understand the principle of operation, but 75 it is not intended as marking the boundaries of

the invention which are to be ascertained from the claims.

What I claim as new and desire to secure by Letters Patent is—

1. Automatic flow control means comprising a valve, a lever that is arranged to control said valve and a float that is arranged to actuate said lever, characterized by a transmission between the float and the lever that includes a worm revolvable by movement of the float and a worm gear sector that is in engagement with the worm.

2. In a flow control apparatus of the character described wherein a variable hydrostatic head above an outlet orifice is controlled for stable delivery capacity, a supply conduit, a receiving conduit, a divisional wall therebetween that is provided with an orifice, a valve positioned to vary the effective area of said orifice, a float chamber connected to the receiving conduit, a float that is movable therein under the influence of liquid level, speed reducing transmissions between the float and the valve that are effective to reflect a comparatively great movement of the float as a small movement of the valve and a differential portion of said transmissions that is effective to cause the movement of the valve to conform to the laws of hydraulic flow through an orifice, so as to cause substantially constant flow through said orifice under varying hydrostatic heads.

3. In a float controlled valve for a sewage system to control flow from a lateral to a trunk sewer, a valved conduit, a movable valve cooperative therewith, a float member positioned to be sensitive to hydrostatic head above said valved conduit and a transmission between the valve and the float that is in part a differential reducing motion device that is effective to move the valve to maintain substantially uniform discharge capacity thereof under varying hydraulic heads.

4. In a flow control means, a chamber that is positioned to receive flow from a conduit, a needle valve adjacent the bottom of the chamber, a conduit positioned to receive discharge from the 45 valve, a float well positioned adjacent the said chamber that is in hydraulic communication therewith, a float in said well, means constraining the float to vertical reciprocating movement, a threaded nut carried by said float, a threaded 50 shaft that is rotatable by said nut and transmission means between the shaft and the valve that are effective to transform rotative motion thereof into varying reduced reciprocating motion of the valve.

5. Float control means for reciprocating a valve in reduced differential movement with respect to the movement of the float, comprising a means limiting movement of the float to reciprocating vertical motion, a rotative shaft, helical 60 cooperative connections between the float and the shaft that are effective to rotate the shaft when the float moves, a worm of varying pitch made rigid with the shaft, a worm gear sector engaged with the worm, a needle valve, and 65 transmissions operatively arranged between the sector and the valve that are effective to move the valve proportionately to the movement of the sector.

6. A float controlled valve for a water system 70 comprising a valve seat member provided with an opening, a cooperative valve, a float positioned adjacent said valve that is sensitive to supply volume for said valve, and differential transmissions between the said float and said valve 75

that include a worm rotatable under the influence of the float and a worm gear sector that is in engagement with said worm, whereby the flow through the valve is substantially constant under varying hydrostatic heads thereabove.

5. 7. A float controlled valve for a water system comprising a valve seat member provided with an opening, a cooperative valve, a float positioned adjacent said valve that is sensitive to 10 supply volume for said valve, transmissions between the said float and said valve that include a worm rotatable under the influence of the float and a worm gear sector that is in engagement with said worm, characterized by a thread of 15 differential pitch on the worm to compensate for varying friction coefficients of water passing through the valve.

8. Flow control means comprising a valved flow portal, a float positioned adjacent the portal 20 on the intake side thereof, guide means for restricting float movement to a vertical plane, a rotative member operatively connected to said float that is rotatable in synchronism with the movement of the float and a differential transmission mechanism operatively arranged between 25

the rotative member and the valve that is effective to control the same to pass substantially uniform quantities of fluids under varying hydrostatic heads.

9. Flow control means comprising a valved 5 flow portal, a float on the intake side thereof that is sensitive to hydrostatic heads over the portal, a worm that is reversely revoluble by movement of the float, a differential thread on the worm, a worm gear sector engaged with the thread 10 of the worm, and transmissions operably connected to the said sector that are effective to differentially vary the flow volume through the portal under the influence of the thread.

10. In hydraulic flow control means, a valve, 15 a float that is positioned to be sensitive to the supply head above said valve and reducing transmission mechanisms between said float and said valve that tend to close the valve as the head above it increases, characterized by a differential 20 portion of said transmission that is effective to compensate for the difference in flow friction through the valve as the same tends to be limited by action of the float.
